[57] CLAIM

The ornamental design for a jacket hood with adjustment strap, as shown and described.

DESCRIPTION

FIG. 1 is a front perspective view showing my new design for a jacket hood with adjustment strap, the jacket shown in dotted lines is for illustrative purposes only;

FIG. 2 is a right side view, the opposite side being a mirror image thereof;

FIG. 3 is a rear view thereof;

FIG. 4 is a top view thereof;

FIG. 5 is a bottom view thereof; and,

FIG. 6 is a front perspective view illustrating the adjustment strap on the hood in an altered position to close the opening to the jacket hood, the jacket shown in dotted lines is for illustrative purposes only.
